UNITED STATES PATENT OFFICE

150,223

DESIGN FOR A COMBINED READING LAMP, BANK, AND SMOKING STAND

Willard H. Graham, Lansing, Mich.

Application April 9, 1947, Serial No. 138,269

Term of patent 14 years

(Cl. D48—20)

To all whom it may concern:

Be it known that I, Willard H. Graham, a citizen of the United States of America, residing at Lansing, in the county of Ingham, and State of Michigan, have invented a new, original, and ornamental Design for a Combined Reading Lamp, Bank, and Smoking Stand, of which the following is a specification, reference being had to the accompanying drawing, forming part thereof.

I claim:

The ornamental design for a combined reading lamp, bank, and smoking stand, as shown.

WILLARD H. GRAHAM.
